UNITED STATES PATENT OFFICE.

HARRY C. WAITE, OF CHICAGO, ILLINOIS, ASSIGNOR TO WAITE TRACTOR COMPANY, OF CHICAGO, ILLINOIS, A CORPORATION OF ILLINOIS.

DESIGN FOR A TRACTOR-BODY.

49,133.

Specification for Design.

Patented May 30, 1916.

Application filed January 25, 1915. Serial No. 4,388. Term of patent 14 years.

To all whom it may concern:

Be it known that I, HARRY C. WAITE, a citizen of the United States, residing at Chicago, in the county of Cook and State of Illinois, have invented a new, original, and ornamental Design for a Tractor-Body, of which the following is a specification, reference being had to the accompanying drawing, forming part hereof.

Figure 1 is a side elevation of a tractor

body showing my new design; Fig. 2 is a top plan view of the same, and Fig. 3 is a front elevation of the same.

I claim:

The ornamental design for a tractor body, as shown.

HARRY C. WAITE.

Witnesses:

D. C. THORSEN,

F. M. RONDEAU.
